UNITED STATES PATENT OFFICE

144,828

DESIGN FOR A LAMP OR SIMILAR ARTICLE

Howard Asch, New York, N. Y.

Application August 8, 1945, Serial No. 121,325

Term of patent 7 years

(Cl. D48—20)

To all whom it may concern:

Be it known that Howard Asch, citizen of United States and resident of New York city, in the county of New York and State of New York, has invented a new, original, and ornamental Design for a Lamp or Similar Article, of which the following is a specification, reference being had to the accompanying drawing, forming part thereof, and in which,

Fig. 1 is a front perspective view of a lamp or similar article, embodying my new design; and

Fig. 2 is a side perspective view thereof. The appearance of the left side and rear of the base is the same as the appearance of the right side. The appearance of the rear of the globe is plain.

I claim:

The ornamental design for a lamp or similar article, substantially as shown and described.

HOWARD ASCH.
